CLAIM

The ornamental design for a wall grommet, as shown and described.

DESCRIPTION

FIG. 1 is a front, top, right side perspective view of a wall grommet assembly comprising a new, original and ornamental design;

FIG. 2 is a front view thereof;

FIG. 3 is a right side view thereof;

FIG. 4 is a left side view thereof;

FIG. 5 is a front, top, right side perspective view of a bottom wall grommet comprising a new, original and ornamental design;

FIG. 6 is a front view thereof;

FIG. 7 is a right side view thereof;

FIG. 8 is a left side view thereof;

FIG. 9 is a front, top, right side perspective view of a top wall grommet comprising a new, original and ornamental design;

FIG. 10 is a front view thereof;

FIG. 11 is a right side view thereof; and,

FIG. 12 is a left side view thereof.

In the drawings, the broken lines are for the purpose of illustrating environment only and form no part of the claimed design.

1 Claim, 6 Drawing Sheets
